James M. Roe

United States Patent Office.

JAMES M. ROE, OF WORCESTER, MASSACHUSETTS, ASSIGNOR TO HIMSELF AND J. R. TORREY, OF SAME PLACE.

Letters Patent No. 87,973, dated March 16, 1869.

IMPROVED SADDLE-LOOP FOR HARNESS.

The Schedule referred to in these Letters Patent and making part of the same.

Know all men by these presents:

That I, JAMES M. ROE, of the city and county of Worcester, and Commonwealth of Massachusetts, have invented certain new and useful Improvements in Saddle-Loops for Harnesses, and other purposes; and I do hereby declare that the following is a full, clear, and exact description of the same, reference being had to the accompanying drawings, forming a part of this specification, in which—

Figure 1 represents a perspective view of my improved saddle-loop;

Figure 2 represents a side view of my improved loop, made in a different form;

Figure 3 represents a cross-section on line A B, fig. 1;

Figure 4 represents a side view of a device for facilitating the manufacture of my improved loop;

Figure 5 represents a cross-section on line C D, fig. 4;

Figure 6 represents an end view of another device, for facilitating the manufacture of my improved loop;

Figure 7 represents a section on line E F, fig. 6;

Figure 8 represents a plan and perspective view of the parts from which the loop is made;

Figure 9 represents a section on line G H, with the parts in position, preparatory to forming the creases or configurations upon the outer piece C of the leather;

Figure 10 represents a cross-section on line I K, fig. 8; and

Figure 11 represents a plan view of the bottom, or inner piece of leather used to make loops in the common way.

To enable those skilled in the art to which my invention belongs, to make and use the same, I will proceed to describe it more in detail.

The nature of my invention relates to the peculiar mode, or manner of making loops for harness-saddles, as will be hereafter explained.

In the drawings, the parts marked A and B represent two loops, made according to my improved mode.

The loop is composed of three pieces, C, D, and E.

The piece C forms the outer surface, when the loop is completed. Patent leather is usually employed for this purpose.

The part marked D is made of leather, rubber, or any other suitably-elastic material, such as paper.

Piece D may be called a grooved, or corrugated pad, the edges, a, b, c, and d, being bevelled off on one side, to render the shape of the loop more perfect, while the convex face, or side is formed with longitudinal grooves, e.

The grooved pad D is placed upon the piece of leather E, and secured in any suitable manner, after which the patent-leather covering C is placed over the grooved pad D, and its edges, f, f, turned under the piece E, as shown in fig. 10, and the edges secured in any proper manner.

The three pieces are now placed over a smooth former, G, and the creasing-device, shown in figs. 4 and 5, applied to draw the wires g into the grooves e, thereby pressing the leather facing C into all of the grooves e,

at the same time, thus forming a perfect and durable loop, in a very cheap and expeditious manner.

The device employed to draw the wires g into the grooves e, is made, or composed of the screw-plate H, screw I having a thumb-head, J, and a yoke, K.

The ends of the wires, on one side, are fastened to the back of the screw-plate, while the ends of the wires, on the other side, are fastened to the bottom of the yoke K.

To prevent displacement or entanglement of the wires g, a thin metal plate, m, is fastened to them, just under the yoke K.

The yoke K draws into a notch, h, in the front of the screw-plate H.

By turning the screw I, wires g may be drawn into the grooves e with any desired degree of force.

A plate, M, having a hole, n, to receive the point o of screw I, is fastened to the plane edge of the former.

In lieu of the creasing-device shown in fig. 4, the device shown in fig. 6 may be employed, and which consists of a curved plate, N, provided with ribs, p; the mode of operation being to force the smooth former with the pieces of leather, or other material thereon, into such device, the ribs p forming the creases in the loop.

Saddle-loops for harnesses have heretofore generally been made by grooving out the piece E, as shown in fig. 11, and then placing the patent-leather facing C upon such grooves, and then the creasing performed by a hand-tool or creaser, only one crease being made at a time.

The operation, when thus performed, is slow and expensive, while it requires great caution and skill, in order to avoid injuring the first crease in making the next, and so on; besides, the loop is not so firm and substantial as when made according to my invention.

It will be understood that the creases may be of any desired form or configuration. Also, that cords may be substituted for the wires. Also, any desired number of wires may be used at a time, to form one or more creases or configurations.

Having described my improved harness-loop,

What I claim therein as new, and of my invention, and desire to secure by Letters Patent, is—

1. A loop for harness-saddles, made substantially as first above described, and shown in figs. 1, 2, and 3, of the accompanying drawings.

2. The combination, with the back and face pieces C E of a harness-saddle loop, of a central-grooved pad-piece, D, substantially as and for the purposes set forth.

3. A loop for a harness-saddle, the grooves, or creases 1 of which are formed all at once, or simultaneously, as set forth.

4. The creasing-devices, shown in figs. 4, 5, 6, and 7, for the purposes set forth.

JAMES M. ROE.
